REVOLVING FAN

Henry E. Van Derschaegh, Chicago, Ill.

Application March 25, 1938, Serial No. 198,103

6 Claims. (Cl. 230—254)

This invention relates to improvements in ventilating devices, and has as one of its principal objects the provision of a revolving fan and a simple means for adjusting the rate at which the fan will revolve.

Another object is the provision of a fan and means for mounting the same of such character that the fan may be made to revolve with respect to its mounting at adjustable speeds, there being no mechanical drive means for effecting the rotary movement, such movement being the result of the particular construction and arrangement of the mounting means and the motive power supplied by operation of the fan itself.

Another object is the provision of a revolving fan of the type characterized and which is further adapted for use as an advertising device.

Still another object is the provision of improved mounting means for fan structures, the mounting means being in the form of a hanger bracket adapted for support from a ceiling or a standard and having means for attachment to a fan and so constructed that the fan may be positioned eccentrically relative to the mounting means so as to effect rotation of the fan at predetermined speeds relative to the mounting.

Still another object is the provision in rotary fan structures of mounting means including electrical connection means having movable and stationary contacts and adapted for mounting either in a standard or in a wall bracket.

Viewed from another aspect, it is an object of the invention to provide a revolving fan including a motor, a propeller driven by the motor, a mounting arm adapted for attachment to a bracket or a supporting base, and means attached to the motor for mounting the same adjustably in eccentric positions relative to the mounting arm, the mounting arm and motor being revolvable relative to the main support.

Other objects and novel aspects of the invention reside in certain details of construction, form, location or operation of the mechanisms hereinafter described in view of the drawings, in which:

Fig. 1 is a perspective view of one form of the fan and ceiling mounting bracket therefor;

Fig. 2 is an enlarged vertical section through the ceiling bracket or mounting, as viewed along lines 2—2 of Fig. 1;

Fig. 3 is a horizontal section showing parts in plan of the ceiling bracket, looking up along lines 3—3 of Fig. 2;

Fig. 4 is an enlarged side elevation of the fan structure of Fig. 1;

Fig. 5 is a top plan detail of the adjustable connection between the fan and bracket arm, as viewed in the direction of lines 5—5 of Fig. 4;

Fig. 6 is a side elevation of a modified form of the invention showing a portable mounting; 5

Fig. 7 is a rear elevation of the adjustable attaching yoke for the portable type of device in Fig. 6.

Referring to Fig. 1, a preferred embodiment 10 of the invention includes a fan arranged to simulate an airplane and having a motor 10 disposed in the nose portion of a fuselage 11 provided with wings 12 and an adjustable airfoil or rudder 13 in the tail of the fuselage. The motor 15 10 is equipped with a fan or propeller 14, thus completing the simulated plane.

Novel means for securing the fan to a wall portion such as the ceiling includes a hanger or bracket arm 16 depending from a wall bracket 20 generally indicated at 17 and arranged to rotate about its longitudinal axis relative to the bracket.

At its lower end, the hanger arm 16 is provided with a gooseneck or laterally offset portion 18 including a horizontal arm 19 extending laterally on both sides of the center or axis of the hanger arm 16.

Attached to the fan above the wings 12 is an adjustable mounting cleat 20 having a bore 21 (Fig. 5) split as at 22, with the split portions 30 joined by a threaded member or bolt 23 adapted to draw the complementary members of the cleat together to clamp a mounting member such as the horizontal extension 19 of the gooseneck firmly therein.

Referring conveniently between Figs. 1, 4 and 5, it will be apparent that by loosening and tightening the bolt 23, the fan may be shifted horizontally or laterally relative to a center through the long axis of the hanger arm 16. 40 Stated in other terms, the adjustable clamping means 19—20 makes it possible to shift the mounting of the fan on opposite sides of a center line through the long axis of the arm 16. The importance of this feature will become clear as 45 the operation of the novel fan is described hereafter.

Means for rotatably mounting the hanger arm 16 in the bracket 17 includes a base plate 26 (Fig. 2) adapted for attachment to a wall or ceiling 50 portion by any usual means and having a central annular flange 27 in which is mounted the stationary race 28 of a radial thrust bearing member including a movable race 29 secured or threaded onto the upper end of the arm 16. 55

A casing member or mounting cup 30, having a bore 31 in one axial end and which is adapted to fit over the shaft 16, has its open upper end portion fitted over the flange 27 and is secured to the latter by means such as the set screw 32. In the bottom of the mounting cup is a recess 33 in which is seated one race 34 of a thrust bearing, the companion race 35 of which embraces the hanger shaft 16 beneath a collar 36 thereon which transmits the hanging load from the arm 16 into the bearing unit 34-35.

Commutating or moving contact means for the motor circuit connections includes an insulating sleeve 40 fitted over the portions of the arm or shaft 16 between the bearings and having secured thereon a pair of spaced contact rings 41 and 42, each of which is connected by conductors 43 and 44 extending down through the hollow portions of the arm 16 and out the open end portion of the gooseneck extension 19 where they issue as a twisted pair 45 (Figs. 4 and 5) and enter the fuselage for connection with the motor 10.

Mounted in insulated sleeve studs 46 and 47 in the cylindrical wall portion of the cup 30 are spring-urged brush contacts 48 and 49, respectively, bearing against the commutator or contact rings 41 and 42. The brushes 48 and 49 are connected by conductors 50 with a source 30 of electric power.

The mounting means is preferably enclosed in a shell or cover bell 51 having a bore in its lower end fitting loosely over the hanger arm 16 and secured by screw means 52 to a flange portion 33 on the mounting base 26.

Thus, it will be apparent that the mounting arm 16 is free to rotate about its long axis as a center in bearing means 28-29, 34-35; the fan, which in the present instance simulates an airplane, rotating either concentrically or eccentrically with relation to the same center depending upon the adjustment of the mounting cleat 20 on the gooseneck arm 19.

For purposes of convenience in describing the movement of the fan structure, particularly when its path of travel is eccentric of its mounting or support, the vertical axis through the supports 16 or 104 is regarded as a center, and the orbit or path of the device may be eccentric to, this center or the device may move about this center. The rotational movement of the fan structure is therefore referred to as orbital movement, and the center of this path, whether concentric with or eccentric to the axis of the support as a center, is referred to as the orbital center.

By sliding the bracket 20 to one or the other position toward opposite ends of the gooseneck arm 19, the eccentricity of the fan structure with relation to the fixed or orbital center of the mounting means or hanger arm 16 may be varied for the purpose of varying the rate of rotation of the fan structure relative to this center, the greater the eccentricity the faster the speed at which the fan revolves.

The speed at which the fan revolves about its orbital center may be controlled not only by adjustment of the eccentric mounting means, but also by turning the airfoil or air-deflecting means providing the rudder 13 in various positions on opposite sides of its normal center line, the degree of control afforded by the rudder being considerable, so that as between adjustment of the rudder and the eccentric mounting, the speed of orbital movement of the fan about the vertical axis of the mounting means which con-

stitutes its center may be accurately determined.

An additional feature of the invention resides in a novel advertising attachment which includes a moving sign element cooperable with the revolving fan means.

Referring to Fig. 4, one form of the advertising attachment includes a collar 60 dimensioned to slide freely on the hanger arm 16 and provided with a set screw 61 by means of which the collar 60 may be clamped into any desired position. Extended from the collar is a horizontal arm 62 having a ball member 63 threaded on its end and there being a vertical shaft 64 threaded into the ball at right angles to the arm 62 and constituting a pivot or spindle upon which a sign bearing structure is rotatably seated for movement about an axis substantially parallel with or collateral to the vertical axis of the upright support or hanger arm 16, which constitutes an orbital center for the fan.

The sign structure may include a pair of metal plates 65 arranged back to back and having opposite horizontal edge portions turned up to provide card-engaging grooves 66 along top and bottom horizontal edges of the frame members, the latter being secured together by any suitable means, such as soldering or the like. Fitted into a vertical slot in the center of the combination frame members is a metal sleeve 67 having a pair of fiber collars 68 arranged in its opposite ends and embracing the spindle 64 so that the frame structure is freely rotatable about the spindle, the latter being shouldered as at 69 to space the frame from the ball 63, and sign cards 35 70 may be worked into the grooves 66.

A modified form of construction particularly adapted for application to portable fans and the like is shown in Fig. 6 wherein a motor 80 of usual construction is provided with a fan 81 and mounted between the upright arms 83 of a special trunnion or yoke bracket including a tubular stud 84 secured by nuts 85 to the lower ends of the arms 83, the upper ends of these arms being attached by wing nuts 86 threaded into the frame of the motor.

An optional feature is the provision of a tail structure formed by a pair of spaced rod or wire arms 87 bent back near their respective mid portions to provide eyes or bights 88 and having their respective free end portions secured by means such as the nuts 89 to the motor frame. Pivotally mounted on a tight-fitting pin 90 extended through the eyes 88 in the tail wires is a rudder or adjustable airfoil 91, which is manually turned into a desired position of adjustment in which it will remain set by virtue of the tight fit of the mounting means 88-90.

An advertising attachment including an arm 92 attached at an offset end portion 93 to the motor frame, is provided with a vertical spindle 94 similar to the spindle 64 of Fig. 4, and which extends substantially parallel to the vertical axis through the mounting means 104, and upon which is seated a sign carrier 95 identical in construction with that described in conjunction with Fig. 4. The spindle 94 is attached by means of a wing nut 96 to the mounting arm 92 so that it may be selectively positioned in a vertical plane to vary the movement and appearance of the sign means 95.

Means for mounting the fan motor upon a portable standard includes a base member 100 having a vertically extending bore, near the upper end of which is a shoulder formation 101 75

upon which is seated the stationary race 102 of a bearing member, the movable race 103 of which embraces an upright mounting arm 104 similar to the arm 16 heretofore described.

- 5 A cast sleeve cap 105 having an endwise bore 106 is fitted over the shaft 104, the latter having a thrust collar 107 disposed within the cap and adapted to bear against a bearing member 108 which in turn rests upon a collar 109 threaded 10 into the cap 105. Thus, the vertical component of the load from the fan structure is distributed to the bearing member 108, while the sidewise or radial thrusts are distributed to the bearing 102-103. The sleeve cap 105 is provided with a 15 set screw 110 for clamping the same to the upright sleeve portion of the base 100.

Moving contact means for the arrangement of Fig. 6 includes a cylindrical plug 112 of insulating material having a stud portion 113 threaded into 20 the bore of the mounting arm 104 at the lower end thereof inside the tubular portion of the base 100. Secured in spaced relation about the cylindrical plug 112 are a pair of contact rings 114 and 115, each connected to one of the conductors 25 of a twisted pair 116 entering a slot near the upper end of the arm 104 and led through suitable openings in the insulating plug 112 for connection with the contact rings. Mounted in suitably insulated sleeves 117 and 118 in the upright tubular portion of the base 100 are spring-urged brushes, each bearing against one of the contact rings 114-115 and each connected with one of the conductors of a twisted pair 119 led exteriorly of the base 100 for connection with the power 30 outlet. An adjustable eccentric mounting for the fan structure of Fig. 6 is shown particularly in Fig. 7, and includes a split mounting sleeve 120 having a threaded cap portion or bore which screws onto the threaded upper end portion 121 35 of the arm 104, the complementary flange portions 122-123 of the sleeve being adjustably drawn together by a bolt 124 in much the same manner set forth in conjunction with the mounting of Fig. 5. The stud or horizontal component 40 45 84 of the mounting yoke is slidably received in the split sleeve and is dimensioned so that the same, and hence the motor 80, may be shifted laterally of the arm 104 into positions on opposite sides of a center line coincident with the longitudinal axis of the support 104, the bolt 124 being drawn up to clamp the yoke or trunnion of the motor into a selected position.

The operation of the modified form of the invention shown in Figs. 6 and 7 is substantially 50 55 the same as that described in conjunction with the device of Fig. 1, with the exception, of course, that the support in the former embodiment is portable, and there are structural differences in the supporting means.

Both embodiments may be adjusted to various 60 positions eccentric of their mountings, and such adjustment will determine the rate at which the fan members, including the propellers, motors, and equipment incident thereto, will revolve. In 65 both embodiments, the propellers 13 and 91 may be set to provide further control for the rate at which the fan devices revolve about their orbits. In both devices, the sign-carrying members 65 and 95 are free to rotate about vertical axes eccentric to the orbital axes of their respective fan 70 devices, and the behavior of these movable sign carriers is such that as their respective fan devices rotate about their respective orbits, the several signs slowly rotate about their own axes as 75 a result of the movement of air by the propellers

and also as a result of the orbital movement of their respective supporting means.

Various changes in details of construction, operation and location of the parts specifically described for illustrative purposes herein may be 5 made without departing from the spirit of the invention, which is not to be limited to such specific details except as may be provided hereinafter in the appended claims.

Having thus described my invention, what I 10 claim as new and desire to protect by Letters Patent is:

1. A revolving fan including a mounting base, an elongated supporting arm mounted on said base for rotation about the long axis of the arm, 15 an electric fan including a revoluble fan element and means adjustably mounting said fan upon said arm and including a yoke-like supporting bracket engaging said fan at points on opposite lateral sides of the axis of revolution of the fan, said bracket having a portion adjustably engaged by means on said arm for movement in the lateral direction of the long axis of the arm, so that the axis of said fan element may be positioned to extend transversely through or eccentric of the axis 20 of said arm, together with movable and stationary contact means arranged in said base for connecting said fan with a source of power.

2. A revolving fan including a mounting base, 30 an elongated supporting arm mounted on said base for rotation about the long axis of the arm, said arm having an offset portion extending laterally on opposite sides of said axis, an electric fan including a revoluble fan element and means mounting said fan adjustably on said offset portion of the arm so as to dispose the axis of rotation of said fan element laterally of the long axis of said arm and in various selected positions through or on opposite sides eccentrically of a 35 center coincident with said long axis of the arm 40 whereby to effect movement of said fan in an orbit about said center at a rate dependent upon the degree of eccentricity of said fan relative to said center, and means arranged in said base for connecting said fan with a source of power.

3. A revolving fan including a mounting base adapted to rest upon a support, a supporting arm mounted on said base for rotation in an upright position about the long axis of the arm, an electric fan including a revoluble fan element, mounting means at the upper end of said arm and including a bracket member supporting said fan and means mounting the bracket for movement in directions laterally of the long axis of said arm 55 so that the axis of rotation of said fan element in preselected positions on opposite sides of said long axis of the arm to vary the rate of travel of the fan, together with commutating contact means arranged in said base for connecting a 60 source of power with said fan.

4. In a device of the class described including electric fan means, means for mounting said fan for rotative movement by air displacement, said means comprising a mounting base, an arm arranged for rotation about its own long axis on said base, said arm having a goose-neck formed at its free end opposite the base, and including a lateral portion extending on opposite sides of said long axis, said fan means including attaching 70 means shiftably engaging said lateral portion of the goose-neck for movement of the fan means into and out of positions eccentric or concentric of said long axis, and means for securing said attaching means in positions of adjustment, and 75

means for connecting said fan means with a source of electric power.

5. In a rotating fan in combination an electric motor, a fan driven by said motor, and means for mounting said motor and fan for displacement about an orbital center, said means comprising a base structure, a supporting arm mounted on said base structure for movement about its own long axis, a mounting yoke adjustably mounted at the 10 free end of said arm for movement in directions laterally of the long axis thereof into and out of eccentric or concentric relationship with said axis, means for securing said mounting yoke in positions of adjustment, means attaching said

motor in said yoke, and means for connecting electric power with said motor.

6. In a rotating fan of the type in which the fan is mounted to revolve orbitally relative to a center, the combination with said fan of display 5 means including a carrier adapted to receive a sign element and constituting an airfoil, and means mounting said carrier on said fan means for rotative movement about an axis extending in parallelism with an axis through said orbital center and at a side of said last mentioned axis which is opposite the fan element of said fan means.

HENRY E. VAN DERSCHAEGH.
